UNITED STATES PATENT OFFICE.

SIMON M. FRANK, OF ST. LOUIS, MISSOURI.

NECKWEAR AND THE METHOD OF MAKING THE SAME.

1,215,319.

Specification of Letters Patent.

Patented Feb. 6, 1917.

Application filed October 9, 1915. Serial No. 55,052.

To all whom it may concern:

Be it known that I, SIMON M. FRANK, a citizen of the United States, residing at the city of St. Louis, in the State of Missouri, have invented certain new and useful Improvements in Neckwear and the Method of Making the Same, of which the following is a specification.

This invention relates to neckwear, and specifically to neckties or scarfs or the like, and to a method of making the same. It has for its object to provide an improved article of the character described and a novel method of making the same, and is especially adapted for use on neckties or scarfs made of any suitable material and cut to the proper shape and folded to make the completed article, there being a suitable lining material between the folds of the necktie or scarf material, said lining running through all or part of the knot-tying portion and, if desired, extending also through the neck-band portion of the tie or scarf.

Particularly in the case of ordinary lined neckties or scarfs or the like when worn with turned-down or double-fold collars, it is well known that it is often very difficult to adjust the tie or scarf between the folds of the collar, and frequently the strain results in the folding or shifting of the lining within the tie, causing the tie to be pulled out of shape, which prevents it from being tied neatly and often destroys its further usefulness. Without such pulling, the lining sometimes wrinkles or curls.

The present invention provides a necktie having a lining of improved construction, resulting in an article of the character described, which may be very conveniently applied in association with a turned-down or double-fold collar without injuring the tie or causing the lining to fold, and one in which the lining will lie flat, and, moreover, the article embodying the present invention may be manufactured with great economy in the use of material employed by means

of the herein-described method at a greatly reduced cost.

Heretofore various expensive and inconvenient methods have been employed to attach the lining to the tie in such manner that the stitches will not show on the front of the tie. One of these methods is to stitch the lining to the back fold of the tie by hand, which is a very tedious and expensive operation and is, therefore, undesirable. Another method is to use a blind-stitch machine for stitching said lining to said back fold, but this method is, also, undesirable because the plunger of the blind-stitch machine causes injury to the face material of the tie, particularly in the case of satin-finished fabrics, and, also, in employing a blind-stitch machine for this work the tie must be pressed in an incomplete state before being inserted in the machine, as otherwise, owing to the uneven surfaces and ends presented by the material of the tie, the machine will not do accurate and satisfactory work, and upon completion of the tie it must again be pressed to give it the smooth and finished appearance to make it a salable article. Moreover, a blind-stitch machine is a very special piece of machinery, expensive as to original cost and, also, maintenance, and, therefore, and because of the loss in interest on money invested in the machine, constantly adds to the cost of ties in the making of which it is used. Still another of these old methods is that of sewing the lining to the back fold of the tie before the tie is made into tubular form, with the back seam adjoining one of the longitudinal edges of the tie. This method is objectionable in that it gives but little freedom in designing the shape of the tie. Any method which prevents the seam of the finished tie from being substantially in the center of the back of the tie interferes with the graceful lines demanded by the trade and the public and makes the product comparatively unsalable.

The method embodying the present invention is one which provides for the exercise of wide scope in designing the shape of the finished necktie with an economical use

of material, and provides that the lining of this invention may be sewed in place on the part that is to form the back fold of the tie before the tie is folded into shape, 5 this sewing being done by means of an ordinary sewing machine without having the stitches show on the front or outside of the front part of the tie, and, moreover, after folding over the parts which form the back 10 folds of the tie, the seam may be sewed by means of an ordinary sewing machine and will run along the back of the tie substantially centrally thereof, it being necessary to press the tie only once, and that after all 15 work of sewing has been finished thereon and when the tie is ready to be packed for shipping or the like. The finished tie embodying the present invention will be a shapely article, strongly reinforced where 20 reinforcement is necessary to provide a durable tie that the wearer will be able readily to tie neatly and readily adjust in relation to a turned-down or double-fold collar, and which can be manufactured by means of 25 the method of this invention at a great saving in the expenditure of time, labor, material, and investment in machinery.

In the accompanying drawings forming part of this specification, in which like numbers of reference denote like parts wherever they occur,

Fig. 1 is a plan view looking at the back of the tie and showing a form of stitching for sewing the lining to said back, a 30 portion of the tie material having been broken away to show a portion of said lining;

Fig. 2 is a view in cross-section, on an enlarged scale, on the line 2—2, Fig. 1;

Fig. 3 is a plan view looking at the back of an end portion of the tie, a portion of the neck-band and the other end portion having been broken away, showing an alternate form of stitching for sewing the lining 45 in position in association with the end portion illustrated;

Fig. 4 is a fragmentary plan view of the portion from which the end portion corresponding to the end portion shown in Fig. 3 50 is formed, said Fig. 4 showing the reverse or inside of the tie material with the lining sewed thereon before the parts are folded to form the tie;

Fig. 5 is a fragmentary plan view showing the end portion shown in Fig. 4 folded to form the tie with the back seam running substantially centrally of said back and with the tie turned inside out as it is just after it leaves the machine by which said central 60 seam is sewed; and

Fig. 6 is a view in cross-section, on an enlarged scale, on the line 6—6, Fig. 5.

The finished necktie 1, best seen in Fig. 1, is formed by folding an appropriately- 65 shaped piece of material of any suitable

character in the manner hereinafter more particularly described, a portion of which material is shown in its open or unfolded position in Fig. 4. Before the material is folded to form the necktie, lining 2 in the 70 large end or main knot-tying portion 3 of the tie is sewed in place on the reverse side of the unfolded or open tie material by means of stitchings 4, Figs. 1, 2, 4, 5, and 6, or by stitchings 5, Fig. 3, the courses of said 75 stitchings 4 and 5 being hereinafter more particularly described, and may, of course, be varied from the particular forms shown and described in any suitable manner adapted to attach said lining to the tie material 80 for the purpose of the present invention.

Lining 2 may consist of two pieces of material of any suitable character disposed relative to each other and the large end or main knot-tying portion 3 of the unfolded 85 tie material substantially as best seen in Fig. 4, in which the two pieces of material forming lining 2 are disposed opposite to each other and extend longitudinally of said large end or main knot-tying portion 3 with 90 one longitudinal edge of each piece of said two pieces of lining material marginally spaced away from the adjacent longitudinal outer edge of said main knot-tying end of the tie material and with the other longitudinal edges of said two pieces of lining material spaced apart on said unfolded tie 95 material at a distance corresponding substantially to the width of the finished folded tie.

Stitchings 4 may run across the lower end portion of each of the two pieces forming lining 2, thence adjacent to the edge of each piece of tie material, which edge is adjacent to the longitudinal outer edge of the unfolded tie material, thence upwardly toward the upper end portion of each of said pieces, thence across on a curve toward the inner longitudinal edge of each of said pieces as disposed on the unfolded tie material, thence longitudinally of said edge for any suitable distance, and thence on a curve across the width of each of said pieces to meet or intersect the opposite longitudinal line of stitchings, 100 the course of stitchings 4 as herein described being shown in relation to the two pieces of material forming lining 2 and in relation to the unfolded tie material in Fig. 4 and being shown in relation to the finished or 105 folded tie in Figs. 1 and 2, and being also, shown in relation to the tie in an intermediate stage in Figs. 5 and 6 between the unfolded position of the material shown in Fig. 4 and the finished or folded tie of 110 Fig. 1.

The two pieces of material forming lining 2 may, if desired, be extended longitudinally to extend through neck-piece 6 and into the other end portion 7 of the tie, said 115 extensions being shaped to conform to the 120

shape of said neck-piece and said other end portion and being spaced appropriately apart on the unfolded tie material a distance corresponding substantially to the width of said neck-piece and other end portion of the folded or finished tie; and said extensions may be sewed to the unfolded tie material by means of stitchings 8, which stitchings may run in substantially two parallel lines 10 longitudinally of said extensions adjacent to the longitudinal edges of said extensions, which edges are adapted to extend spaced apart from each other on the unfolded tie material, said stitchings crossing the width 15 of said extensions adjacent to each end of said extensions, it being, of course, understood that said stitchings 8 may follow any other suitable course and may be otherwise disposed than herein specifically described 20 and shown.

Any suitable stitchings adapted for sewing the extension of lining 2 borne between the folds of neck-band or neck-piece 6 may be substituted for the stitchings 8 particularly-described and shown, and, moreover, 25 said extension of lining 2 through neck-piece 6 may be omitted in a tie and the method of making the same embodying this invention, or stitchings 8 or substitute stitchings 30 therefor may be used on neck-piece 6 for the purpose of reinforcing same with or without the extension of lining 2 being disposed through said neck-piece.

Instead of sewing the two pieces of material forming lining 2 to the unfolded material of the large end or main knot-tying portion 3 of the tie by means of stitchings 4, said pieces may be sewed to said unfolded material by means of stitchings 5, shown in 40 Fig. 3, in which said stitchings 5 run from adjacent to the lower end of each of said pieces longitudinally adjacent to the edges thereof, which are disposed along the adjacent outer edges of said unfolded tie material, to the other end of said pieces, thence across each piece on a curve to the opposite longitudinal edge of said piece, thence along 45 said opposite edge marginally thereof to the lower end of said piece, thence across on a curve substantially tangentially of the initial portion of said stitching or to pass beyond said initial portion to the adjacent longitudinal edge of each of said pieces.

It is, of course, understood that stitchings 4 and 5 are herein particularly described and shown by way of convenient illustration and that any suitable stitchings adapted for sewing the two pieces of material forming lining 2 to the unfolded tie material of the 50 large end or main knot-tying portion 3 in the manner disclosed by this invention may be substituted for said stitchings 4 and 5.

By means of sewing said two pieces of material forming lining 2 to the reverse side 60 of the unfolded tie material of the large end

or main knot-tying portion 3, as described herein, by means of stitching 4 or stitching 5 or substitute stitchings therefor, and by means of sewing the pieces of material forming the extension of lining 2 for neck-piece 6 to the reverse side of the unfolded tie material of said neck-piece by means of stitchings 8 or substitute stitchings therefor, it will result that no portions of said stitchings will be visible on the front or 70 show side of the folded or finished tie, either on the large end or main knot-tying portion 3 or on neck-piece 6 or on end portion 7, and said stitchings may be made with an ordinary sewing machine, thus avoiding 75 the greater cost of making such stitchings by means of the expensive blind-stitch machines or by means of tedious and very expensive hand-sewing, which are the usual processes used when a lining is sewed in 80 place within a tie by sewing from the outside of the back of a folded tie with the lining between the fold after the tie has been formed by said folding.

Moreover, the lining 2 of a tie embodying 90 the present invention being formed of two pieces of material divided longitudinally and spaced appropriately apart on the reverse side of the unfolded tie material and sewed thereto, as hereinabove described, the 95 back seam 9, formed by sewing together the outer edges of the unfolded tie material after said edges have been brought together by folding over to the right and left the portions of the unfolded tie material bearing the two pieces of material forming the 100 lining 2, will be substantially central of the back of the folded and finished tie, thus permitting great latitude in designing ties of 105 varied shapes of graceful outlines and having, furthermore, the great advantage that said back seam 9 will not be exposed to view 110 when the tie is being worn, a result which is not achieved in ties of a construction in which the lining is of one piece having a longitudinal edge sewed to one of the longitudinal edges of the unfolded tie material and then having the other longitudinal edge 115 of said unfolded tie material folded over upon and sewed to said first-named longitudinal edge of the tie material to which the adjacent edge of said lining is attached and then sewing up said two edges of said lining to form the seam of the tubular form of the tie, which seam will lie adjacent to a longitudinal edge of the finished or folded tie in a 120 position in which it is liable to show when the tie is worn and in which it will certainly be exposed to view should the slightest carelessness in tying the tie cause said seam to 125 twist slightly toward the front, thus detracting from neatness and a desired elegance of appearance.

It will be observed that the unfolded tie material, Fig. 4, with the two pieces form- 130

ing the lining 2, is folded to the position shown in Fig. 6 with the lining 2 on the outside of the back of the tie, which permits of seam 9 being sewed up quickly and conveniently by means of an ordinary sewing machine without the necessity of turning in or otherwise finishing the rough edges of said seam, for said edges will be on the inside of the back of the tie when 5 said tie is in finished shape, the process of turning the tie from the inside-out position shown in Fig. 5 to the right-side-out position shown in Fig. 1 being accomplished by drawing an end of the inside-out form 10 shown in said Fig. 5 through the tubular form upon itself in the manner, for instance, of turning a stocking inside out or the reverse.

The tie having been turned right side out 20 to the position shown in Fig. 1, same may be pressed as the final step in finishing the tie.

If desired, a piece of binding tape 10 or the like may be sewed to back seam 9 simultaneously with the sewing up of said seam, 25 said tape sewed up with said seam in the manner described being adapted as a well-known seam-reinforcing means.

It is, of course, understood that stitchings 30 or substitute stitchings therefor may, if desired, be sewed on neck-piece 6 after the tie has been turned right side out from the position shown in Fig. 5 to the position shown in Fig. 1, and that said stitchings may be made by means of an ordinary sewing 35 machine and may pass through and may be visible on both the back and front of the neck-piece 6 of the finished tie, the fact that said stitchings show on both the back and front sides of neck-piece 6 in the finished 40 tie not being objectionable, particularly in the case of a tie worn with a turned-down or double-fold collar, because in that case said neck-piece lies between the fold of the collar and said stitchings thereon will not 45 be exposed to view.

Briefly restated, the method of making a tie embodying this invention consists in cutting a piece of tie material of a shape adapted to the desired shape of the finished 50 tie, placing said tie material flat and open upon a surface with the reverse side of said tie material upward, placing upon said upwardly-turned reverse side two longitudinally-divided pieces of suitable material for 55 forming lining 2, sewing said two pieces on said reverse side in the position shown in Fig. 4 with a longitudinal edge of each of said pieces adjacent to an outer longitudinal edge of said flat-lying tie material and with 60 the other longitudinal edges of said pieces spaced apart on said tie material a distance corresponding substantially to the width of the finished tie, bringing together said 65 outer edges of the flat-lying tie material by means of folding each portion of said tie

material bearing one of said pieces sewed thereto to the right and to the left with said pieces turned outwardly and with said edges so brought together extending longitudinally substantially centrally between 70 the outer edges of the folded form shown in Fig. 5, sewing up the seam 9 at said edges brought together as described, said seam being sewed with or without reinforcing tape 10, turning the form shown, in fragment, in Fig. 5 from the inside-out position shown in said Fig. 5 to the right-side-out position shown in Fig. 1, and then pressing the tie in said right-side-out position.

Various changes in the details of the 80 method and in the arrangement of stitches and arrangement and construction of parts may be made without departing from the nature and spirit of the present invention.

While two pieces 2 of lining material for 85 the main knot-tying portion are mentioned in this specification, yet it is within this invention so to divide those pieces as to pluralize the same or any other number or arrangement of pieces of lining material 90 may be used or practised.

I claim:

1. The herein-described method of making a necktie, said method comprising extending a piece of tie material shaped appropriately to the form of the finished tie, dividing an appropriately-shaped piece of lining material into a plurality of parts, sewing each of said parts to the reverse side of said extended tie material, one edge of 95 each of said parts being adjacent to the outer edge of said extended tie material and another of the edges of said parts being spaced apart on said extended tie material a distance corresponding substantially to the 100 width of the finished tie, folding the portions of said extended tie material bearing said parts to the right and left, respectively, to bring the outer longitudinal edges of said 105 extended tie material together substantially 110 centrally of the folded form with said parts on the outside, sewing said edges together to form a seam, said folded and seamed form now being tubular, and reversing or turning said form inside out to bring said 115 parts forming said lining inside the tubular form to form the finished necktie.

2. A scarf or similar object of suitable fabric folded and shaped in a flat hollow form and embodying a relatively narrow 120 portion intermediate its ends and wider end portions and a lining extending through the main part of the length of said scarf, said lining being formed of an appropriately-shaped piece of material divided longitudinally into a plurality of parts, said parts being sewed to the reverse side of the tie material independently of each other.

3. A necktie composed of a piece of suitable fabric having on its reverse side lapped 125

130

edges of said fabric, said edges being sewed together to form a longitudinal seam substantially centrally of said reverse side, and a lining of suitable material between said 5 reverse side and the body portion or front of the said tie, said lining being divided longitudinally into a plurality of parts, said

parts being sewed on the inside of the said reverse side portion independently of each other, an edge of each of said parts being 10 adjacent to one of said lapped edges.

In testimony whereof I hereunto affix my signature.

SIMON M. FRANK.
